UNITED STATES PATENT OFFICE.

FREDERICK GEORGE HEATH, OF HEADLESS CROSS, NEAR REDDITCH, ENGLAND.

DESIGN FOR A HOLDER FOR SECURING CROCHET-BALLS TO THE USER'S WRIST.

46,126.

Specification for Design.

Patented July 21, 1914.

Application filed April 6, 1914. Serial No. 830,058. Term of patent 7 years.

To all whom it may concern:

Be it known that I, FREDERICK GEORGE HEATH, subject of the King of Great Britain, residing at St. Georges Works, Birchfield Road, Headless Cross, near Redditch, in the county of Worcester, England, have invented a new, original, and ornamental Design for Holders for Securing Crochet-Balls to the User's Wrist, of which the following is a specification, reference being had to the accompanying drawing, forming part thereof.

The figure is a perspective view of a holder illustrating my new design.

I claim:

The ornamental design of a holder for securing crochet balls to the user's wrist as shown.

FREDERICK GEORGE HEATH.
